 Heywood-Wakefield Company, Boston, Mass.,
 a corporation of Massachusetts

Application August 3, 1932, Serial No. 627,314

4 Claims. (Cl. 155—55)

This invention relates to improvements in chairs, and it consists of the matters hereinafter described and more particularly pointed out in the appended claims.

5 The primary object of the invention is to provide a chair which is indeed comfortable for the occupant and in which the seat is mounted for a teetering action with respect to the chair frame or base.

10 Another object of the invention is to provide a chair wherein the front end of the seat frame is pivotally connected to the chair frame or base, while the rear end of said seat frame is pendently supported from said chair frame or base by elastic or flexible means, whereby the occupant may readily set up an easy and comfortable teetering or rocking action of the seat frame.

15 A further object of the invention is to provide a chair, wherein the rear end of the seat frame is pendently supported at its rear end by flexible or elastic means formed to provide the arm rests for the chair.

20 The above mentioned objects of the invention, as well as others, together with the many advantages thereof, will more fully appear as I proceed with my specification.

In the drawings:

25 Figure 1 is a perspective view of a chair embodying the preferred form of the invention;

30 Figure 2 is a longitudinal vertical sectional view through the same as taken on the line 2—2 of Figure 3;

35 Figure 3 is a bottom view, in elevation of the improved chair, with the legs which form a part of the chair frame or base shown in section;

40 Figure 4 is a detail transverse vertical sectional view on an enlarged scale through a part of the improved chair as taken on the line 4—4 of Figure 3; and

45 Figure 5 is a detail longitudinal sectional view on the scale of Figure 4, through a part of the improved chair as taken on the line 5—5 of Figure 4.

50 In general, my improved chair comprises a suitable chair frame or base and a seat frame, the latter carrying a back rest frame. The seat frame which may be suitably upholstered is pivotally mounted at each side toward the front from the chair frame. Said seat frame is also pendently supported at each side toward the rear from the chair frame or base by elastic means thereon and which means in this instance, is so arranged as to form the arm rests for the chair as a whole. When the seat is occupied, a teeter-

ing action of the seat frame may be easily set up by the occupant.

5 Referring now in detail to that embodiment of the invention, illustrated in the drawings: 1 indicates as a whole a substantially rectangular horizontally disposed chair frame or base which includes side rails 2—2 and front and rear rails 3 and 4 respectively, suitably mounted at the corners upon front and rear pairs of supporting legs 5 of any suitable character. As shown herein, 10 the rear rail 4 is in the form of a bar disposed at an elevation lower than that of the front rail and which bar connects the legs of the rear pair together.

15 Associated with the chair frame is a substantially rectangular seat frame 6 of a width and depth from front to rear, a trifle less than that of the chair frame. Said seat frame includes side rails 7—7 and front, intermediate and rear rails 8, 9 and 10 respectively. Parallel with said side rails are bars 11 for the support of the coiled springs 12 for the seat cushion 13 when such a frame is intended to support an upholstered seat.

20 Normally the seat frame is so disposed with respect to the chair frame that the front rail 25 of the seat frame overhangs but is spaced only slightly above the front rail of the chair frame. Each side rail of the seat frame is spaced a short distance inwardly from the plane of the associated side rail of the chair frame.

25 Associated with the rear end of the seat frame is a back rest 14 which includes a suitably shaped frame, including horizontally disposed top, intermediate and bottom bars 15, 16, 17 and upright side bars 18—18 respectively. When so desired the back rest may be upholstered to accord with the seat.

30 To support the back rest with respect to the seat there is provided a pair of L-shaped straps 19—19, each having a part 20 secured to the underside of the rear and intermediate rails of the seat frame and each having a part 21 extending upwardly at the rear side of the back rest frame and secured to the bottom and intermediate rails 17 and 16 thereof. By means 45 of said L-shaped straps, the back rest while suitably supported from the seat frame, is capable of a limited forward and rearward yielding movement.

35 On the inner face of each side rail of the 50 chair frame, near its front end is an inwardly offset strap 22. To each strap 22 is pivoted the bottom end of a link 23, the top end of which is fixed to an associated side rail of the seat frame as best shown in Figure 5. By this ar- 55

angement, the seat frame is pivotally supported from the chair frame upon an axis disposed to the rear of and below the top of the front rail of the seat frame.

5 On each side rail of the seat frame at its rear end is fixed an outwardly offset strap 24 whereby the rear end of the seat frame is pendently supported from a point above the seat by means later to be described and including an 10 elastic or flexible member.

To coat with said straps 24 in elastically supporting the rear end of the seat frame from above, I provide means which may also function as the arm rests for the chair. At each 15 side of the chair I provide a U-shaped spring member including top and bottom legs 25-26 connected together at the front end by a semi-circular bend 27. Each spring member is preferably made from flat spring stock bent to suitable shape and the bottom leg 26 of each member is fixed to the top edge of an associated side rail 2 of the chair frame as by means of through bolts. Each leg 25 sweeps rearwardly in a shallow reverse curve, and fixed to the rear 20 end thereof is an L-shaped clip 28 to which the top end of a normally perpendicular link 29 is pivoted. The bottom end of said link is pivotally connected to an associated strap 24 before mentioned on the rear end of each side 25 rail of the seat frame. Preferably but not necessarily so, the top leg of each U-shaped side member has an arm rest finishing member 30 secured to its top side and extending substantially the full length thereof.

30 It is pointed out that the arm rests 30 which are suitably secured to the members 24, also rigidifies the same so that the flexing takes place where intended and namely, at the bends 27.

When the chair is occupied, it is apparent 40 that a substantial amount of weight of the occupant is imposed near the rear of the seat frame. Thus by a movement well-known the occupant can set up a teetering action in the chair, the arm rests flexing in the bends 27 to 45 allow such movement and which movement is comfortable and restful for the occupant. While the arm rest members permit such a teetering action, the top legs 25 thereof have only a limited longitudinal movement if any at all, but such 50 movement is not sufficient to permit any forwardly and rearwardly shucking of the seat frame with respect to the chair frame or base. Thus while the seat is unoccupied it is quite stable but when occupied, may be readily teetered to the enjoyment of the occupant.

All of the parts permitting such teetering movement except the arm rests are so arranged 60 as to be substantially concealed from view so that when the chair is unoccupied, there is nothing to visibly indicate that it is capable of a teetering action. Thus while the chair is made

for comfort, it readily fits in with other furniture without detracting from the appearance of the same.

While in describing the invention, it has been set forth as embodied in a chair but this is to be considered only as illustrative as it also may be embodied in other articles of furniture and therefore I do not wish to be limited thereto, except as may be specifically set forth in the appended claims.

10 I claim as my invention:

1. A chair or like article of furniture embodying therein, a base and a seat, means for pivotally connecting one end of the seat to said base, a horizontally disposed U-shaped spring having top and bottom legs connected together at one end, one leg of each spring being fixed to each side of said base and the other leg of each spring being disposed in a plane above the seat and a link having pivotal connections with the other end of said other leg of each spring and with the opposite end of the seat respectively.

2. A chair or like article of furniture embodying therein a base and a seat, means for pivotally connecting the front end of the seat to said base, a spring member mounted on each side of the base and including a rearwardly extending flexible portion disposed above its associated side of the seat and a link pivotally connected at one end to the rear end of said rearwardly extending portion of each spring member, said links each being pivotally connected at its other end with the rear end of the seat.

3. A chair or like article of furniture embodying therein a seat and a base, means pivotally connecting the front end of the seat to said base, a substantially U-shaped spring member at each side of the base and each including top and bottom, rearwardly extending spring arms one fixed to an associated side member of the base and the other spaced above said side member and links, one between the free end of each rearwardly extending top spring arm and the rear end of the seat and pivotally connected to the latter.

4. A chair or like article of furniture embodying therein a base and a seat, means for pivotally connecting the front end of the seat to said base, a spring member mounted on each side of the base and including a rearwardly extending portion disposed above its associated side of the base, means operatively connecting the rear end of said rearwardly extending portion of both spring members with the rear end of the seat, arm rest members supported on said spring members and a back rest member supported from the seat at the rear end thereof in a manner permitting a limited amount of forward and rearward movement.

60 LEWIS LARSEN.
